UNITED STATES PATENT OFFICE.

PERCY GARDNER, OF NEW YORK, N. Y., ASSIGNOR TO GARDNER & HIGGET CO., OF NEW YORK, N. Y., A CORPORATION OF NEW YORK.

RIBBON-DISPLAY CABINET.

1,098,897.

Specification of Letters Patent.

Patented June 2, 1914.

Application filed November 21, 1913. Serial No. 802,198.

To all whom it may concern:

Be it known that I, PERCY GARDNER, a citizen of the United States, residing in the city of New York, borough of Manhattan, in the county and State of New York, have invented a certain new and useful Improvement in Ribbon-Display Cabinets, of which the following is a specification.

The invention relates to boxes or containers for holding and displaying ribbons, braids and analogous goods put up in stick form, and the object of the invention is to provide a light inexpensive cabinet in which such goods may be mounted and conveniently displayed for selection by the purchaser.

The invention consists in certain novel features of construction and arrangement by which the above objects are attained, to be hereinafter described.

The accompanying drawings form a part of this specification and show the invention as it has been carried out in practice.

Figure 1 is a front elevation of a filled cabinet in the open condition. Fig. 2 is a corresponding end view. Fig. 3 is a vertical transverse section of the same in the closed condition. Fig. 4 is a plan view of the cabinet, partially filled and with the cover omitted. Fig. 5 is a transverse section through a portion of the cabinet, on a larger scale. Fig. 6 is a face view of one of the small packages or sticks of ribbon.

Similar letters of reference indicate the same parts in all the figures.

The body of the cabinet is rectangular in plan view, formed of pasteboard by the usual paper box methods and having its front A preferably of less height than the back A¹, and its ends A² A² of corresponding shape with the upper edge of each inclined upwardly from the front to the back as shown. The bottom A³ is preferably extended slightly on all faces to form an ornamental flange.

B is a hinge of paper, reinforced by a strip of fabric if preferred, extending along the top edge of the back A¹ and flexibly joining the latter to the back C¹ of the cover which is similar in construction to the body and has a front C equal in height to the back A¹ of the body, and inclined ends C² C² from the free edge of such front to the hinge, so that when closed the cover will

overlap upon the body and its contents at 55 the front and ends and offer the desired rectangular form of cabinet.

D is a flexible strap attached to the ends A² C² of the body and cover respectively, to maintain the latter while in the raised or 60 open position.

Within the body, preferably on a level with the top edge of the front A is a horizontal deck F filling the whole area of the body and having a plurality of small rectangular apertures f arranged in parallel rows longitudinally of the body. The deck is of pasteboard scored along the margins and bent to form the flanges F¹ by which it is glued to the interior of the body at the 70 desired height therein. The apertures f are of a size to receive snugly the goods to be held and displayed.

G is a sheet of pasteboard, scored and folded or bent as shown to produce a series 75 of continuous pockets G¹ having converging sides, secured to the under face of the deck F, one pocket for each row of apertures f, with the wide upper portion of each matching approximately to the side margins of 80 such apertures. The angular pockets extend at a forward inclination from the under face of the deck F toward and preferably to the upper face of the bottom A³.

The material to be held and displayed 85 may be understood to be narrow ribbon M wound lengthwise upon a strip of pasteboard M¹, and secured by a band M² of paper around the middle, leaving the ends of the ribbon exposed to view. The sticks thus 90 formed are inserted in the apertures f, one in each, and forced downwardly into frictional engagement between the angular walls of the pockets which by reason of the V-shape and resiliency grasp the ends of 95 the sticks gently but with sufficient strength to resist successfully the slight displacing strains or shocks to which the cabinet is subjected in handling and transportation.

When the cover is turned back the goods 100 are displayed projecting from the deck in inclined ranks, each stick exposed for examination by the purchaser without the usual danger of damage by handling and consequent soiling in making a selection, 105 and the selected sticks may be easily removed without disturbing the others.

The pockets G¹ and holes f may be so

shaped and located relatively to each other as to display the sticks all inclined backward at approximately the same angle, or so arranged that one or more of the ranks may stand at a different inclination to the rest. 5 In the drawings the rear rank is shown as less inclined or more nearly perpendicular than the others thus permitting the width of the cabinet to be reduced while displaying 10 such rank to advantage by reason of the slight elevation of the ends of its sticks above the ends of the forward ranks. The sticks may be easily removed and replaced as desired in arranging the goods attractively and in making sales and replenishing 15 stock, and the cabinet may be ornamented as desired to enhance the attractiveness of the display.

The simple pasteboard construction is exceedingly economical in manufacture and well adapted for the display of the class of goods described. In constructing the cabinet to contain and display other classes of goods it may be made of more substantial 25 materials adapted for a longer term of service.

I claim:—

1. In a device of the character set forth, a body portion, a deck therein having apertures arranged in rows, a series of pockets 30 beneath said deck arranged parallel with said rows, secured to the under face of said deck and lying at an inclination thereto, said pockets having converging sides constructed to receive and engage frictionally 35

the ends of goods in stick form inserted through such apertures.

2. In a device of the character set forth, a body portion, a deck therein having apertures arranged in rows, a series of pockets 40 beneath said deck arranged parallel with said rows, secured to the under face of said deck and lying at an inclination thereto, said pockets having converging sides extending from the margins of such apertures, and 45 constructed to engage frictionally the ends of goods in stick form inserted through such apertures, and a cover for said body adapted to inclose said deck and the goods thereon.

3. A device for the purpose described, 50 comprising a body portion, a deck therein and having apertures, and a plurality of pockets formed of one continuous piece of material secured to the under side of said deck, said pockets extending at a forward inclination from the under face of the deck and bearing against the bottom of the body portion and each with converging sides to form a tapered pocket to frictionally grasp the end of goods in stick form, the open end 55 of each pocket being coincident with an aperture in the said deck.

In testimony that I claim the invention above set forth I affix my signature in presence of two witnesses.

PERCY GARDNER.
